UNITED STATES PATENT OFFICE.

WALTER H. COFFILL, OF OAKLAND BEACH, RHODE ISLAND.

MUFFLER.

1,113,410.

Specification of Letters Patent.

Patented Oct. 13, 1914.

Application filed December 22, 1913. Serial No. 808,075.

To all whom it may concern:

Be it known that I, WALTER H. COFFILL, a citizen of the United States, residing at Oakland Beach, in the county of Kent and State of Rhode Island, have invented certain new and useful Improvements in Mufflers, of which the following is a specification.

My invention relates to mufflers intended for controlling the exhaust of engines and 10 motors and especially adapted for boats.

The essential objects of my invention are to relieve the muffler chamber of the accumulation and compression of the burnt gases and substances which choke the muffler chamber and create a back pressure upon the motor or engine, and which the regular gas outlet is inadequate to relieve; further, to provide a means for cooling the muffler that will avoid the accumulation of water in the muffler chamber and its overflow therefrom to the motor through the gas inlet as is now occasioned in mufflers having water inlets and outlets opening into the muffler chamber, especially in motor boats; and further 25 to enable the muffler to be located at a point below the water line.

A further object is to efficiently cool the muffler without precipitating the substances held in the gases within the muffler chamber 30 to the water outlet in the bottom thereof, and thus choking the water outlet and fouling the muffler walls.

Another object is to minimize the number of fittings and enable the same muffler 35 to exhaust from either side of the boat by merely reversing the muffler.

To the above ends primarily my invention consists in such parts and combinations of parts as fall within the scope of the appended claims.

In the accompanying drawings which form a part of this specification, Figure 1 is a side elevation of my muffler, Fig. 2, a section of the same taken on line $\alpha\alpha$ of 45 Fig. 3, and Fig. 3, a section taken on line $\gamma\gamma$ of Fig. 2.

Like reference characters indicate like parts throughout the views.

My muffler comprises a preferably spherical casing indicated in a general way by 1, provided near its circumference with the usual gas inlet 2 extending from the casing tangentially thereto to form the exhaust inlet pipe 3, connected with the exhaust pipe 4 of an internal combustion engine or motor. An outlet 6 is also provided in the casing

in alinement with the inlet, and is extended tangentially to the casing to form an exhaust pipe 7 in alinement with the exhaust inlet pipe 3. In the pipe 7 is located a shut off valve 9.

Below the described inlets and outlets, and at right angles thereto is an outlet pipe 11 located in the casing wall, having a portion 12 extending within the casing to a point 65 near the center of the muffler chamber 14, and having a portion 15 projecting externally of the casing, and to which is connected, in the present instance, by a collar 18 or otherwise a pipe 20 leading to the atmosphere. In a threaded opening 22 in the casing is an externally threaded plug 24 in alinement with the pipe 11 and movable by means of its threaded connection into contact with and away from said pipe. Integral 75 with the end of the plug exterior of the casing is a head 26 to accommodate a wrench, and loose upon the member 24 is a lock nut 27 adapted to coöperate with the exterior surface of the casing. As usual in this type 80 of muffler the burnt gases enter the inlet 2, and rotating in the direction of the arrows shown in Figs. 2 and 3 escape through the pipe 11. The plug 24 controls the volume of gas which is permitted to pass through the 85 last mentioned pipe.

The described operation of the muffler results in compression of the gases and foul accumulations in the chamber 14 which must be removed at intervals to secure satisfactory operation. At such times the valve 9 is opened, and the gas passes directly through the pipes 3 and 7 drawing with it the old gases and matter accumulated in the muffler chamber.

In order to reduce the temperature of the muffler due to the high temperature of the gases passing therethrough, and to effect this end without direct contact of the cooling liquid with the gases, which would 100 precipitate the matters in the gases and thus foul the interior of the muffler, the casing 1 is composed of an inner shell 28 and an outer shell 30, spaced from each other to form an intermediate spherical 105 chamber 31, and connected by circular webs 32, 33, 34, and 35, surrounding the members 3, 7, 11 and 24 respectively. At diametrically opposite points in its top and bottom the shell 30 has openings 37 and 38, in which are fixed respectively the water inlet and water outlet pipes 39 and 40.

The water is forced by a pump or otherwise from any source of water supply into the chamber 31 where it circulates between the surfaces of the shells, and escapes through the pipe 40. Thus the temperature of the entire casing is lowered

What I claim is,—

1. In a muffler of the type set forth, the combination of a substantially spherical casing provided with an exhaust gas inlet and a discharge gas outlet both tangentially disposed with relation to the casing and in alinement with each other, and with a gas outlet located at right angles to the discharge outlet, and means for closing the discharge gas outlet.

2. In a muffler of the type set forth, the combination of a substantially spherical casing provided with an exhaust gas inlet and a discharge gas outlet both tangentially disposed with relation to the casing and in alinement with each other, and with a gas outlet located axially of the casing at right angles to the discharge outlet, a valve in the discharge outlet, an outlet pipe located in the gas outlet and extending into the cas-

ing, and a plug adjustably mounted in the casing in alinement with the outlet and extending into the casing.

3. In a muffler of the type set forth, the combination of a casing comprising a spherical inner shell and a spherical outer shell spaced from the inner shell and provided with tangentially disposed adjacent openings, a web surrounding the openings and connecting the shells, also provided with tangentially disposed adjacent openings in alinement with the first mentioned openings, a web surrounding the last mentioned openings and connecting the shells, also provided with adjacent openings axially of the shells, a web surrounding the last mentioned openings and connecting the shells, and pipes located in the openings within the webs.

In testimony whereof I have affixed my signature in presence of two witnesses.

WALTER H. COFFILL.
